FIG. 5.

BY:

Phil J. Nawn
ATTORNEY

INVENTOR:

Ernest A. Anheuser.

UNITED STATES PATENT OFFICE.

ERNEST A. ANHEUSER, OF MILWAUKEE, WISCONSIN.

FILE.

Application filed January 24, 1927. Serial No. 163,260.

This invention relates to those abrasive tools classified as files or rasps, and particularly the class of files employed at finishing pressed metal forms which are later treated with a final coat for attaining a highly glossed, or, perfectly smooth surface.

The objects of this invention are to provide an element used in smoothing out rough surfaces that may occur about welded or soldered joints that unify sheet metal parts; the uneven surfaces of solid areas; the reduction of objectionable protuberances, such as, bumps, pitted indentures, and extraneous deposits which disfigure those surfaces intended to have the finish and smoothness of glass, be it flat, curved, or a combination of both; the eliminating of defective work occasioned by faulty equipment, irrespective of, and beyond the control of skilled labor; providing a means whereby skilled labor of a lower grade can function with greater accuracy, thereby economically producing a greater volume of work in a time period that was heretofore required to produce a lesser volume with labor of the expert grade in skill; the devising of means whereby a common stock article of manufacture is employed for attaining an abrasive element that formerly required a particular and uncommon form of stock as a base for gaining a hand operated tool; the providing of an abrasive tool having compound arcuately fashioned teeth crossing an originally flat bar to present a convex surface along a toothed face which may be on the opposite sides of the bar as well; providing a flexible tool adapted for attaching same to a determinedly curved holder or handle means that avoids the objectionable occurrence attending the bending of a flat element which assumes form wherein the longitudinal medial area is lower than are the edges of said area, leaving the edges aforesaid inclined to inordinately and unavoidably dig into a metal surface to an excess that is admitted to be slightly in excess, but sufficient to roll up metal that in turn forms a tooth itself which scores the surface noticeably. If the adjacent surface is not shaved down to the depth of the objectionable score, the defect becomes glaring when

the work is brought to its finally polished stage; again, if the surface is not reduced to the scored level in an expertly worked fashion, the whole spot, clumsily treated, becomes a defect that forces a rejection of the work itself and an appreciable loss in labor consequent thereto. The variance of the convexity from a flat plane in this regard, is not above several thousandths of an inch; however, this rise will insure against any possibility of a concave condition being present in a tool of this class. A method and means for manufacturing, to gain the aspects here set forth, are disclosed in my co-pending application, filed January 6th, 1927, Serial Number 159,305, now U. S. Letters Patent No. 1,710,466.

Other advantages will be remarked in the particular description and pointed out in the appended claims; also, illustrated in the several figures seen in the drawing, all of which form part of this application.

The views chosen to set forth this invention are:

Fig. 1 is a view showing the adaptation of this kind of file.

Fig. 2 is an enlarged fragmentary plan view.

Fig. 3 is an edge view of Fig. 2.

Fig. 4 is an enlarged section on line 4—4 of Fig. 2.

Fig. 5 is a diagrammatic view of an opposite objectionable condition.

Similar characters of reference apply correspondingly throughout the illustrations.

An automobile body B, or a like structure is constructed of sheet metal parts, sometime steel, but largely aluminum; the parts are joined together by brazing, soldering, or riveting; these jointures leave rough surfaces that must be smoothed down by some quick method that will leave the metallic surfaces as smooth and as accurately contoured as are the gently curved bodies made of filled woodwork and smoothed by a rubbing process that employs pumice stone. However, this non-scoring product is ineffective on metal which must be finished with a steel harder than itself. Hand tools of the file or rasp variety are used for this work by skilled

and rapid artisans, on whose adeptness depends the faultless quality demanded, and the numerical volume necessary, to keep this part of, especially automobile manufacturing, abreast of those other branches which can move at a faster rate in speedy and progressive production schedules.

The file, or, rasp R is made from flat bar stock which is rectangular in cross section. 10 The formed or cut bar is severed into required lengths that, in many instances, are attached to a fixedly bent handle H, although the files frequently enough have tangs for receiving the customary well-known wooden grip. Fig. 1 shows an application of the tool in work necessary on auto bodies or any similar structure where the joints are quickly made and consequently left in a roughened state to be filed smooth, as are any other defects that depart from a rigidly accurate curvature absolutely essential to gaining a perfect finality.

Fig. 2 is a plan view of the bar R having a partially milled file surface T provided with 25 arcuate parallel teeth that offer a cutting edge 1 which forms an arc of a circle across the horizontal face of the bar, whose center is along the longitudinal line m of the said bar. The teeth are undercut as indicated by 30 the dotted line 2, but the said teeth may be serviceable without undercutting in some classes of work, and, further, the teeth may also be arcuately formed horizontally from centers along a non-medial line m', when 35 varying uses demand this preference; the latter form is shown dotted in Fig. 2 radially along the line m'. The transverse cross section of the rectangular bar is changed, in milling, to where its flat face assumes a convex 40 form which is of a segmentary shape that disposes its chord parallel to and above the transverse medial line of the bar's thickness whereon the teeth T occur, this change gives a 45 crowned surface to the complement of teeth, somewhat exaggerated in the said figure, but existing nevertheless to an extent whereby a 50 reverse, or concave, condition cannot possibly present itself. The vertical segmentary formation will, of course, follow the horizontal 55 course of the teeth, and the chordal line will be understood as following the arcuate direction of said teeth in order to complete a segment where the generating line is central as per m, or, incomplete where m' is the generating line. The manual action present in 60 using tools of this sort is a swaying movement that rocks the files transversely, which rocking has a tendency to gouge in the edges of a file when flat faced, and more so if the surface is concave. This contingency requires that flat or concave files be reduced along their 65 longitudinal edges by some method that will lessen the tendency to score should the file rock; a sufficient reason for the prevalent custom wherein the concave surfaced files are

sand-blasted along their edges in an effort to cut down this objected-to characteristic, the mentioned process being an indefinite method of curing a recognized defect in files of the sort referred to. The aforesaid sand-blasting, in many instances, leaves irregular edges that are objectionable but which are not easily detected until the surfaces worked upon betrays them; besides this, the process is an unreliable method for grinding evenly, as such a process should be in conditions of this kind. The present invention eliminates the serious objections in offering a convex surface whereby a dangerous edge cannot prevail, and where the approximating process of sand blasting does not have to be employed for leveling the file's surface.

Fig. 4 indicates, by dotted line, how both faces of the bar may be toothed.

Fig. 5 is diagrammatically enlarged to show the effect present in a concave surface, where the granular particles P crowd towards the center, forming in this way, a cushion that assists in holding the file teeth away from the rasped surface, thereby reducing the tool's efficiency and inducing a rocking of the tool in order to get a cutting result, which invites an edge cut that will produce an ugly score. The entrapped particles, being of varying sizes, are rolled up along the surfaces under the file's concavity and these particles act as abrasive elements themselves which cannot be considered or reckoned with as can a positive and regularly shaped tooth formation. All irregular scores, scratches, and the like, must be eradicated later and the additional labor is a consideration that cannot be tolerated, because of the time loss involved to the manufacturer, and, because of the wage reduction to the employee, who is operating upon a piece-work basis subject to a scrutinizing inspection which rejects work done on, hardly noticeable, blemishes.

Having described my invention what is claimed and desired to protect by Letters Patent, is:—

1. A file formed of flat rectangular and flexible bar stock having, transverse teeth disposed arcuately convex in the horizontal plane, and arcuately convex in the vertically transverse plane of the bar aforesaid, said teeth cut to offer a greater depth at the edges than at the center of the bar aforesaid.

2. A file formed of flat rectangular and flexible bar stock having, transverse teeth disposed arcuately convex in a horizontal plane, and arcuately convex in a vertically transverse plane of the bar aforesaid, said teeth milled to offer uniform cutting edges that are tangent to the top plane of the bar and convexly curved to terminate below the point of tangency at the side edges of the bar's width.

In testimony of which I hereunto affix my signature.

ERNEST A. ANHEUSER.
